(57) **CLAIM**

The ornamental design for a light, as shown and described.

DESCRIPTION

FIG. 1 is a perspective view of an exterior surface configuration of a light;

FIG. 2 is a plan view of the light in FIG. 1;

FIG. 3 is a right side elevational view of the light in FIG. 1, the left side elevational view being a mirror image;

FIG. 4 is a rear elevational view of the light in FIG. 1;

FIG. 5 is a front elevational view of the light in FIG. 1;

FIG. 6 is a perspective view of an exterior surface configuration of a light showing power switch markings in phantom;

FIG. 7 is a plan view of the light in FIG. 6 showing power switch markings in phantom;

FIG. 8 is a rear elevational view of the light in FIG. 6 with power switch markings in phantom;

FIG. 9 is a perspective view of an exterior surface configuration of a light;

FIG. 10 is a plan view of the light in FIG. 9;

FIG. 11 is a right side elevational view of the light in FIG. 9, the left side being a mirror image;

FIG. 12 is a rear elevational view of the light in FIG. 9; and, FIG. 13 is a front elevational view of the light in FIG. 9.

The phantom lines are not part of the claimed invention.
